REFRIGERATING APPARATUS

George C. Pearce, Dayton, Ohio, assignor to General Motors Corporation, Dayton, Ohio, a corporation of Delaware

Application August 23, 1940, Serial No. 353,884

5 Claims. (Cl. 260—83)

This invention relates to refrigerating apparatus and more particularly to controls.

The accuracy of control devices depends upon the accuracy of transmission of movement between the operating means and the control device to be operated, such as a valve or switch. One of the important factors is the pivotal connection of the levers used in transmitting the movement. The usual types of pivotal connections involve friction and have a certain amount of looseness or play which affect the accuracy of the control. These inaccuracies are multiplied when compound leverage devices are used to amplify the movement provided by the operating means.

It is an object of my invention to provide a control having an accurate compound multiplying arrangement.

It is another object of my invention to provide a multiplying arrangement for controls in which no pivot pins are required.

It is a further object of my invention to provide a multiplying arrangement for controls in which the pivotal connections are made substantially frictionless.

Further objects and advantages of the present invention will be apparent from the following description, reference being had to the accompanying drawing, wherein a preferred form of the present invention is clearly shown.

In the drawing:

Fig. 1 is a vertical sectional view disclosing one embodiment of my invention; and

Fig. 2 is a plan view of the control shown in Fig. 1 with the cover removed.

Briefly, I have shown a diaphragm operating a compound multiplying arrangement in which flexible metal connecting members and a rounded adjusting screw are used instead of the usual pivot pins in order to provide a more accurate, more compact and more durable multiplying arrangement for operating the switch mechanism.

Referring now to the drawing, there is shown a frame member 20, formed of heavy sheet metal, and including a base portion 22 and folded-up side portions 24 and 26. Fastened to the base portion 22 is a pancake-shaped diaphragm 28 which has a threaded nipple extending through an aperture in the base receiving a clamping nut for fastening the diaphragm 28 to the base. The nipple connects to the capillary tubing 30 which connects the interior of the diaphragm with some suitable source of control pressure, such as the high or low pressure sides of the refrigerating system.

The opposite or upper face of the diaphragm 28 is provided with a rounded button bearing against a diaphragm follower 32 which is the primary member of the multiplying arrangement used and is analogous to the primary lever of ordinary multiplying arrangements. However, this primary member 32 is made of comparatively heavy metal and at one end is firmly riveted by means of the post 34 to the base 22.

10 This primary member 32 is held in contact with the button upon the upper face of the diaphragm by a heavy compression type coil spring 36 supported at its upper end by a spring follower 38 which in turn is located by a set screw 40. This set screw 40 is threaded through a spring support member 42 which is generally Z-shaped and has projections 44 on opposite sides which are received in notches 46 provided in the upper edges of the side wall portions 24 and 26. The upper portions of the edges of these notches are struck inwardly so as to firmly hold the projections 44 in the bottom of the notches and to oppose any upward movement of the upper portion of the Z-shaped member 42. The lower portion of the Z-shaped portion 42 is supported by a pair of posts 48 which are riveted to the base portion 22.

15 The primary member 32 is provided with an offset end portion 50. Riveted by the rivets 52 to the offset projecting portions 50 at the end of the primary member 32 is a thin leaf spring member 54 which at its other end is riveted by a pair of rivets 56 to the secondary member 58. The secondary member 58 is provided with shoulders 60 which bear upon the mid-portion of the leaf spring member 54 so that the pivot between the primary member 32 and the secondary member 58 is about the lower edges of these shoulders 60 which are in contact with the leaf spring member 54.

20 A set screw 62 is threaded through the center of the lower portion of the Z-shaped spring support member 42 and is provided with a rounded lower end which serves as the normally fixed pivotal support for the secondary member 58. Inasmuch as the primary and secondary members are substantially straight at all times; that is, they are substantially perpendicular to the movement of the diaphragm 28 and the secondary member 58 at all times. There is substantially no friction between the secondary member 58 and the bottom of the set screw 62, since under such circumstances there will be practically no lateral movement of the secondary member 58.

with respect to set screw 62. The set screw 62 is provided with a lock nut 64.

The other end of the secondary member 52 is provided with an aperture 65 for allowing the coil spring 88 to pass through. This other end is also provided with a step-shaped insulating block 66 to which is riveted a flat double spring anchoring member 68. Connected to the spring anchoring member 68 are the toggle springs 70 of a novel type of toggle mechanism. The other ends of these tension springs 70 are connected to the ears provided upon the opposite end of a rigid member 72 which at its other end is riveted by the contact member 74 to a flexible strip of metal 76 which extends in the same direction from the contact 74 as the member 72 and is firmly anchored to the post 78.

This post 78 is firmly riveted to a conductor strip 88 which is positioned in the bottom of a central groove provided in the second insulating block 82 which is fastened to the base by screws, not shown. One of the electrical conductors 84 is connected to the strip 88 while the other electrical conductor 86 is connected to a metal plate 88 riveted to the top of the insulating block 82 and provided at its opposite end with the stationary contact 88 which cooperates with the movable contact 74. An upwardly extending set screw 88, accessible through an aperture in the base, is provided for limiting the opening movement of the movable contact 74 and the rigid member 72. The contact mechanism is suitably insulated by various pieces of insulation from the metal portions of the switch mechanism to prevent arcing.

When the diaphragm 28 expands, it will bend upwardly the free end of the primary member 32. The movement provided by the diaphragm 28 is comparatively small so that this movement is always well within the elastic limit of the primary member 32 and entails no great amount of force. This primary member by its bending movement tends to curl slightly and this provides an increase amplifying movement with respect to a primary lever of equal dimensions. The lower end of the set screw 62 holds the adjacent end of the secondary member 52 from movement. This causes the offset end 68 of the primary member 32 to bear through the leaf spring 84 upon the adjacent edges of the shoulder 68 of the secondary member 52 to pivot the secondary member 52 in a counter-clockwise direction about the lower end of the set screw 62.

Thus the movement of the diaphragm 28, which has been amplified in the primary member 32, is further amplified in the secondary member 52 in proportion to the relative distance between the spring anchoring apertures in the member 68 and the lower end of the pivot pin 62 on the one hand and the distance between the shoulders 68 and the lower end of the pivot pin 62 on the other hand. The tension toggle springs 70 always insure a tension upon the leaf spring 84 and the offset projecting end 68 of the primary member 32 supports the leaf springs 84 in both directions from the shoulders 68 so that no shear stress is exerted upon the leaf springs 84. Since all of the members are riveted together none are likely to become loose and the riveted connections between the primary member and the post 34 and the leaf spring connection between the primary member 32 and the secondary member 52 are substantially frictionless.

The set screw 62 may be employed to adjust the location of the primary and secondary members with respect to the button on the diaphragm

28 in order to coordinate the operation of the switch mechanism and the movement of the diaphragm 28 so that the movement of the diaphragm 28 will take place only within certain limits. This adjustment may also be so set that the primary member moves equally in opposite directions from its natural position. The set screw 40 may be used to control the tension of the compression spring 36 in order to determine the pressures at which the switch mechanism will be operated. Obviously the toggle mechanism could be used to operate a valve or some other control device instead of the contact 74. While it has been mentioned that this switch mechanism may be used on a refrigerating system it is obvious that it is also applicable to other apparatus.

While the form of embodiment of the invention as herein disclosed, constitutes a preferred form, it is to be understood that other forms might be adopted, all coming within the scope of the claims which follow.

What is claimed is as follows:

1. A control including a compound multiplying device comprising a bendable primary member rigidly anchored at one point, a secondary multiplying member bodily carried by and rockably connected directly to the primary member to form a direct pivotal connection between the two members, a pivot for the secondary member, a control device operably connected to one of said members, an operating means operably connected to the other of said members for operating said members and said control device, and means for adjusting said pivot to adjust the relationship between said operating means and the operation of said members.

2. A control including a compound multiplying device comprising a bendable primary multiplying member rigidly anchored at one point, a rigid secondary multiplying member secured by and rockably connected directly to the primary member at another point to form a direct pivotal connection between the two members, a pivot for said secondary member, a control device operably connected to one of said members, an operating means connected to the other of the members to operate the control device.

3. A control including a compound multiplying device comprising a bendable primary multiplying member rigidly anchored at one point, a rigid secondary multiplying member, a leaf spring rockable connection directly connecting the secondary member with another point upon the primary member to form a direct pivotal connection between the two members, a pivot for said secondary member, an operating means connected to the primary member to operate the control device.

4. A control including a compound multiplying device comprising a bendable primary multiplying member rigidly anchored at one point, a rigid secondary multiplying member, a leaf spring rockable connection directly connecting the secondary member with another point upon the primary member to form a direct pivotal connection between the two members, a pivot for said secondary member, an operating means connected to the primary member to operate the control device, and means for adjusting said pivot to vary the relationship between said operating means and the operation of said members.

5. A control including a compound multiplying device comprising a bendable primary multiplying member rigidly anchored at one point, a rigid

secondary multiplying member, a leaf spring rockable connection directly connecting the secondary member with another point upon the primary member to form a direct pivotal connection between the two members, a movable means in operative relationship with the primary member, a movable means in operative relationship with

the secondary member, one of said movable means constituting an operating means for operating the control device, the other of said means constituting an adjusting device for adjusting the operation of the control device.

CERTIFICATE OF CORRECTION.

Patent No. 2,300,697.

November 3, 1942.
GEORGE C. PEARCE.

It is hereby certified that error appears in the printed specification of the above numbered patent requiring correction as follows: Page 2, second column, line 41, claim 2, for "secured" read --supported--; and that the said Letters Patent should be read with this correction therein that the same may conform to the record of the case in the Patent Office.

Signed and sealed this 12th day of January, A. D. 1943.

Henry Van Arsdale,
(Seal) Acting Commissioner of Patents.
